CLAIM

The ornamental design for charging station for electric vehicles, as shown and described.

DESCRIPTION

FIG. 1 is a perspective view of a first embodiment of the charging station for electric vehicles;

FIG. 2 is a front view of the charging station for electric vehicles shown in FIG. 1;

FIG. 3 is a left view of the charging station for electric vehicles shown in FIG. 1;

FIG. 4 is a right view of the charging station for electric vehicles shown in FIG. 1;

FIG. 5 is a back view of the charging station for electric vehicles shown in FIG. 1;

FIG. 6 is a Top view of the charging station for electric vehicles shown in FIG. 1; and,

FIG. 7 is a bottom view of the charging station for electric vehicles shown in FIG. 1.

The key features lie in the appearance of the product.

1 Claim, 7 Drawing Sheets
